G. Spuchler

UNITED STATES PATENT OFFICE.

GEORGE SPUCHLER, OF KANSAS CITY, MISSOURI.

CARD-HOLDER.

1,239,838.

Specification of Letters Patent. Patented Sept. 11, 1917.

Application filed August 31, 1916. Serial No. 117,894.

To all whom it may concern:

Be it known that I, GEORGE SPUCHLER, a citizen of the United States, residing at Kansas City, in the county of Jackson, State 5 of Missouri, have invented a new and useful Card-Holder; and I do hereby declare the following to be a full, clear, and exact description of the invention, such as will enable others skilled in the art to which it app- 10 pertains to make and use the same.

This invention relates to card holders and is particularly adapted to hold cards containing notices relative to the delivery of different articles. For instance, if ice or 15 milk is wanted, or any other article, the card containing the name of the article wanted is placed in the holder, and then the ice man or the milk man seeing the notice, will deliver the amount of ice or milk de- 20 sired.

However, the principal object is to provide a holder for holding cards advertising different articles for sale in a store.

Another object of the invention is to pro- 25 vide a holder consisting of a band, which fits about a post or the like, and is provided with a pair of slidable groove members which may be adjusted to receive and hold cards of different sizes.

30 In practical fields, the details of construction may necessitate alterations falling within the scope of what is claimed.

The invention comprises further features and combinations of parts, as hereinafter 35 set forth, shown in the drawings and claimed.

In the drawings:—

Figure 1 is a view in side elevation of a 40 post, showing the improved card holder applied thereto, and a card held in place.

Fig. 2 is a perspective view of the holder detached from the post.

Fig. 3 is a sectional view on line 3—3 of Fig. 1.

45 Fig. 4 is a sectional view on line 4—4 of Fig. 2.

Referring more especially to the drawings, 1 designates a resilient band, which may be made to conform to irregular con- 50 tours, and constructed to be of such diameter as to fit about posts of different diameters in cross section, and 2 denotes strips having channels 3. The lower ends of the channeled strips are closed by the end walls 4. Secured by rivets 5 upon one face of each

channeled strip 2 is a metallic strap 6. These straps are provided with arches 7, which arch over the band 1, as shown in Figs. 2, 3 and 4, thereby mounting the channeled strips 2 upon the band 1, so that said strips 60 2 may be adjusted toward and from each other, whereby cards of different widths may be supported in the channels of the strips 2. The metallic straps frictionally engage the band 1, whereby the strips 2 65 (which are preferably disposed vertically) may be held frictionally in adjusted positions. The band 1 is resilient or yieldable, so that it may be opened to fit posts of different diameters in cross section, and the 70 ends 8 and 9 of said band overlap, to more securely hold the band in place. The cards 10 may be provided with any suitable advertisement or notice, such as a "For rent" or "For sale", or the notice of different articles 75 for sale or wanted, such as ice, milk, groceries and the like.

It will be seen that after the channel members have been adjusted to hold the desired width of card, and the band 1 has been 80 strapped around a post, the arches of the metallic straps will be held against the cylindrical surface of the post which will provide a means against the displacement of the channel members, which means is in ad- 85 dition to the means provided by the close frictional engagement between the strap and the channel members.

The invention having been set forth, what is claimed as new and useful is:—

In a card holder, the combination of a re- 90 sili ent band and a pair of vertical strips, of metallic straps attached to the strips and in surrounding relation to the band, the strips being channeled and having the chan- 95 nels closed at the bottoms by end walls, the straps being arched and holding the band in close frictional contact with the strips, the outside arched portion of the straps being adapted to frictionally engage the sur- 100 face of the object to which the band is attached, so that they may give the strips additional security against displacement.

In testimony whereof I have signed my name to this specification in the presence of 105 two subscribing witnesses.

GEORGE SPUCHLER.
